UNITED STATES PATENT OFFICE.

LLOYD ESPENSCHIED, OF HOLLIS, NEW YORK, ASSIGNOR TO AMERICAN TELEPHONE AND TELEGRAPH COMPANY, A CORPORATION OF NEW YORK.

REPEATER APPARATUS FOR CARRIER SYSTEMS.

Application filed June 19, 1919. Serial No. 305,389.

To all whom it may concern:

Be it known that I, LLOYD ESPENSCHIED, residing at Hollis, Long Island, in the county of Queens and State of New York, have invented certain Improvements in Repeater Apparatus for Carrier Systems, of which the following is a specification.

This invention relates to repeater circuits and more particularly to repeater circuits adapted for the amplification of high frequency carrier currents.

Where a carrier system is superposed on an ordinary low frequency transmission line such as a telephone or telegraph line and such a line includes a repeater for amplifying the low frequency signals transmitted thereover, it is necessary to make some special provision for amplifying the carrier frequencies transmitted over the line since the low frequency repeater is not so designed as to efficiently amplify the higher frequencies used for carrier transmission. Since it is desirable to superpose the carrier system upon the low frequency system with the least possible change and reorganization of the latter, it is desirable that some arrangement be provided whereby the high frequency oscillations may be amplified without disturbing the low frequency repeater organization.

An important feature of the present invention is the provision of means for amplifying the high frequency carrier oscillations without disturbing the low frequency repeater. This feature as well as other aims of the invention, are realized in a specially designed repeater adapted to amplify all of the carrier frequencies transmitted over the low frequency signalling circuit, and in an arrangement of said special repeater to operate in parallel with the low frequency repeater normally associated with the lines. The invention also provides for substantially preventing the carrier oscillations from being transmitted to the low frequency repeater, and for preventing the transmissions of the low frequency signalling currents to the special high frequency repeater. In this manner the low frequency channel and the high frequency channels are maintained distinct from each other and the high frequency apparatus in the repeater stations may be imposed upon the ordinary low frequency sys-

tem or removed therefrom without materially affecting the organization or properties thereof.

The invention may now be more fully understood by reference to the following description when read in connection with the accompanying drawing, Figure 1 of which discloses a circuit arrangement of one embodiment of the invention and Fig. 2 of which illustrates a modification.

In Fig. 1 ML and ML_1 designate sections of an ordinary low frequency transmission circuit such as a telephone circuit, these sections being interconnected by a two-way repeater of well known construction, comprising amplifiers AE and AW for amplifying currents transmitted in opposite directions. The transmission line sections ML and ML_1 are balanced with respect to the repeater by means of artificial lines MN and MN_1 , respectively. The output circuits 1 and 2 of the amplifiers AE and AW are associated with the transmission line sections and corresponding artificial lines through the usual three-winding transformers T and T' . The input circuits 3 and 4 are associated with the input bridges 5 and 6 through transformers 7 and 8.

The repeater apparatus so far described is of the ordinary construction employed in telephone practice and its operation is well understood. In order to amplify the carrier frequencies, however, a specially designed repeater is necessary. For this purpose the amplifying arrangement shown in the lower part of the diagram is connected to the line sections ML and ML_1 through carrier transmission branches CB and CB_1 . This special repeater includes two one-way amplifying arrangements A_1E and A_1W . Each of these amplifying arrangements consists of a duplex two-stage amplifier of the so called "push-pull" type. The amplifying arrangement A_1E comprises a pair of amplifying vacuum tubes 9 and 10 in tandem with each other and in parallel with another pair of tandem tubes 11 and 12. Similarly the amplifying arrangement A_1W includes a pair of tandem vacuum tube amplifiers 13 and 14 connected in parallel with a similar pair of vacuum tube amplifiers 15 and 16.

The output circuits 17 and 18 of the amplifying arrangements A_1E and A_1W are asso-

ciated through transformers 19 and 20 with intermediate circuits 21 and 22 which are connected through three-winding transformers 23 and 24 with the carrier branches 5 CB_1 and CB , respectively. The input circuits 25 and 26 are associated through transformers 27 and 28 with the input bridges 29 and 30.

Since the carrier frequencies after being 10 transmitted over lines of considerable length will be more or less attenuated, depending upon the frequency, it is desirable that the amplitudes of the several carrier frequencies should be equalized. For this purpose 15 equalizing arrangements 31 and 32 may be provided in the input bridges 29 and 30, respectively. The general principles pertaining to equalizers of this character are fully set forth in the U. S. application of Ray S. 20 Hoyt, Serial No. 242,567, filed June 29, 1918, and as these equalizing arrangements constitute no part of the present invention they need not be described in detail herein. In order to prevent carrier frequencies from 25 being transmitted to the low frequency repeater, low frequency filters LF and LF_1 are provided. While these filters may be of any desired character they are preferably broad band filters of the general type disclosed 30 in U. S. patents to George A. Campbell, 1,227,113 and 1,227,114 dated May 22, 1917. These filters comprise a plurality of sections, each consisting of series inductance and shunt capacity, so designed as to freely 35 transmit frequencies which lie within the limits of ordinary signal transmission, while substantially extinguishing frequencies lying above said limit. In the special case herein illustrated in which the arrangement 40 is applied to telephone transmission the filters LF and LF_1 should transmit with negligible attenuation frequencies lying within the range of ordinary telephone transmission while practically extinguishing 45 higher frequencies. In order to balance these filters with respect to the low frequency repeater, balancing net works LF' and LF'_1 are provided. These balancing net works may be filters duplicating the filters 50 LF and LF_1 , or they may simply be net works so designed as to have electrical characteristics simulating those of the filters.

In order to prevent the transmission of 55 low frequency currents to the high frequency repeater, high frequency filters HF and HF'_1 are included in the carrier branches CB and CB_1 . These filters are also of the general type disclosed in the Campbell patents above referred to and each consists of a plurality 60 of sections comprising series capacity and shunt inductance. The elements of these filters are so proportioned as to freely transmit a band of frequencies above the upper limiting frequency of ordinary signal transmission 65 while substantially extinguishing

currents below said limit. In the particular case illustrated, which applies to telephone transmission, the filters HF and HF_1 would be designed to freely transmit frequencies lying above the upper limits of 70 ordinary telephonic transmission, while extinguishing frequencies lying below said limit. In order to balance the filters HF and HF_1 , balancing net works HF' and HF'_1 are provided. These balancing net 75 works may simply be filters duplicating the filters HF and HF_1 , or they may consist of net works so designed as to have electrical characteristics simulating those of the filters HF and HF_1 . Balancing net works 80 M_1N and M_1N_1 are also provided, these balancing net works being so designed as to simulate the characteristics of the apparatus connected across the terminals of the filters HF and HF_1 . 85

The operation of the circuit may now be readily understood and is as follows: Low frequency currents flowing over the line ML are transmitted over the filter LF and from the input bridge 5, through the transformer 90 7, an input circuit 3, to the amplifier AE . Upon being amplified the currents are transmitted from the output circuit 1, through the transformer T' where the energy divides, part flowing through the filter LF_1 , to the 95 line section ML_1 and part flowing through the balancing arrangement LF'_1 to the net work MN_1 . Low frequency transmission in the opposite direction will take place in a similar manner and need not be described. 100

High frequency carrier oscillations incoming from the line section ML will be transmitted through the high frequency filter HF and over the carrier branch CB to the input bridge 29. After being equalized by the 105 equalizer 31, the carrier frequencies are transmitted through the transformer 27 to the duplex amplifying arrangement A_1E . The construction of this duplex amplifying arrangement is such that the two sides of 110 the circuit are balanced so that substantially no current variations take place in the common paths of the input and output circuits of the tubes connected in parallel and the resultant effect is that of current variation flowing serially over the amplifier conductors indicated by heavy lines. This balanced construction of the amplifying arrangement results in less distortion 115 of the oscillations. The amplified oscillations appearing in the output circuit 17 are transmitted through the transformer 19 and over the intermediate circuit 21, to the three-winding transformer 23, where the energy divides, part flowing over the carrier branch 120 CB , and through the high frequency filter HF_1 , to the main line section ML_1 , and part flowing through the balancing arrangement HF'_1 to the artificial line M_1N_1 . Transmission 125 in the opposite direction takes place in a 130

similar manner and need not be further described.

A modified arrangement is shown in Fig. 2, the arrangement of this figure differing 5 from that of Fig. 1 chiefly in that a common network and balancing transformer are used for balancing the line with respect to both the carrier repeater and the ordinary telephone repeater, while the filtering arrangements for separating the telephone 10 currents and the carrier currents through the proper repeaters are arranged upon the repeater side of the balancing transformer instead of upon the line side. The same 15 reference characters are used to designate elements of this figure which also occur in Fig. 1.

Referring to Fig. 2 the main lines ML and ML_1 are balanced by networks or artificial 20 lines MN and MN_1 , respectively, and transformers 40 and 41 are provided for associating input circuits I — I_1 and output circuits O — O_1 with the main line sections. The input circuit I is provided with a high frequency branch HI and a low frequency branch LI , the former branch including the high frequency filter HFE and the branch LI including the low frequency filter LFE . These filters are similar to filters HF and 30 LF respectively, of Fig. 1, the filter HFE passing a band of frequencies sufficiently broad to include the carrier frequencies of the several carrier channels while excluding frequencies below the upper limit used in 35 ordinary telephone transmission, and the filter LFE passing ordinary telephonic frequencies but substantially excluding higher frequencies. The high frequency branch HI is connected to a repeater unit A_E for amplifying 40 carrier frequencies transmitted from west to east, said repeater having its output circuit associated with a high frequency branch HO_1 of the output connection O_1 , through the high frequency filter HFE_1 , 45 similar to filter HFE . In a similar manner the low frequency branch LI is connected through the filter LFE to an amplifying tube AE for amplifying telephone currents transmitted from west to east. The 50 amplifier AE is connected through a similar filter LFE_1 to a low frequency branch LO_1 of the output connection O_1 leading to the line ML_1 .

The input connection I_1 from the line 55 ML_1 is similarly provided with high frequency and low frequency branches HI_1 and LI_1 , the former being connected through a high frequency filter HFW_1 , similar to HFE , to an amplifier unit AW for amplifying 60 carrier frequencies transmitted from east to west. The amplifier is connected through a filter HFW , similar to HFW_1 , to the high frequency branch HO of the output connection O , to the line ML . Low 65 frequency branch LI_1 is connected through

low frequency filter LFW_1 to an amplifying tube AW for amplifying ordinary telephonic frequencies transmitted from east to west. Amplifier AW is connected through filter LFW , which is similar to LFW_1 , to low 70 frequency branch LO of the output connection O .

In the operation of the apparatus carrier frequencies incoming from the line ML are transmitted to the input circuit I and 75 pass through the filter HFE to the amplifier A_E , being excluded from the amplifier AE by the filter LFE . The amplifier AE amplifies the carrier frequencies which are then transmitted through the filter HFE_1 80 and over the output connection O_1 to the line ML_1 . Ordinary telephonic frequencies incoming from the line ML are transmitted to the input connection I and through the filter LFE to the amplifier AE , 85 being prevented from reaching the amplifier A_E by the high frequency filter HFE . After being amplified, the telephonic currents are passed through the filter LFE_1 and over the output connection O_1 to the 90 main line ML_1 .

Currents incoming from the line ML_1 are transmitted to the input connection I_1 and separated into the branches LI_1 and HI_1 by means of the filters LFW_1 and HFW_1 . 95 The amplifiers AW and A_E then amplify the telephonic frequencies and the carrier frequencies respectively, these frequencies again being combined, after passing through the filters LFW and HFW , in the output 100 connection O from which they are transmitted to the main line ML .

While the invention has been disclosed as applied to a telephone transmission circuit, it is equally applicable to other types of 105 signal transmission, such as, for instance, ordinary telegraph circuits. Where the low frequency range is quite narrow, the low frequency filters may be replaced by any equivalent means having the desired selectivity such as tuned circuits or antiresonant combinations. Similarly, if but one carrier channel is superposed on the low frequency transmission line, the high frequency filters HF and HF_1 may be replaced by some 110 simple form of tuning arrangement.

In general, while it has been deemed desirable in the interest of clear understanding to illustrate the invention as embodied in a specific form of circuit arrangement, 120 it will be obvious that the general principles herein disclosed may be employed in many other organizations widely different from those illustrated without departing from the spirit of the invention as defined 125 in the following claims:

What is claimed is:

1. In a signaling system, a transmission line, a repeater in said line for amplifying a band of low frequency signaling currents, 130

- a second repeater for said line operated in parallel with said first mentioned repeater and adapted to amplify a band of high frequency oscillations of the order used in carrier current transmission, means associated with said first mentioned repeater to substantially prevent the transmission of high frequency currents to said repeater, and means associated with the latter repeater to substantially prevent the transmission of low frequency signaling currents thereto.
2. In a signaling system, a transmission line, a repeater in said line for amplifying a band of low frequency signaling currents, a second repeater for said line operated in parallel with said first mentioned repeater and adapted to amplify a band of high frequency oscillations of the order used in carrier current transmission, means associated with said first mentioned repeater to substantially prevent the transmission of high frequency currents to said repeater, and a broad band filter associated with the second repeater so arranged as to substantially suppress low frequency signaling currents while freely transmitting to said repeater oscillations of carrier frequency.
3. In a signaling system, a transmission line, a repeater in said line for amplifying a band of low frequency signaling currents, a second repeater for said line operated in parallel with said first mentioned repeater and adapted to amplify a band of high frequency oscillations of the order used in carrier current transmission, a broad band filter associated with said first mentioned repeater, said filter being so arranged as to substantially suppress carrier frequencies while freely transmitting to said repeater a band of frequencies within the range employed in ordinary signal transmission, and a broad band filter associated with said second repeater, said filter being so arranged as to substantially suppress frequencies below the upper limit of frequencies used in ordinary signal transmission while freely transmitting a band of frequencies above said limit.
4. In a signaling system, a transmission line adapted to transmit currents lying in different frequency ranges, a plurality of repeaters in said line operated in parallel with each other, means in circuit with one repeater for substantially preventing the transmission of frequencies below a preassigned upper limit, and means in circuit with another repeater for substantially preventing the transmission of frequencies above said preassigned limit.
5. In a signaling system, a transmission line adapted to transmit currents lying in different frequency ranges, a plurality of repeaters in said line operated in parallel with each other, a broad band filter in circuit with one repeater, said filter being so arranged as to substantially suppress frequencies below a preassigned upper limit, and means in circuit with another repeater for substantially preventing the transmission of frequencies above said preassigned limit.
6. In a signaling system, a transmission line, a repeater in said line for amplifying a band of low frequency signaling currents, a second repeater for said line operated in parallel with said first mentioned repeater and adapted to amplify a band of high frequency oscillations of the order used in carrier current transmission, means associated with said first repeater for substantially preventing the transmission of frequencies above the upper limit of frequencies used in ordinary telephonic transmission, and means associated with said second repeater for substantially preventing the transmission of frequencies below said limit.
7. In a signaling system, a transmission line, a repeater in said line for amplifying a band of low frequency signaling currents, a second repeater for said line operated in parallel with said first mentioned repeater and adapted to amplify a band of high frequency oscillations of the order used in carrier current transmission, a broad band filter associated with said first mentioned repeater and so arranged as to substantially prevent the transmission of frequencies above the upper limit of ordinary telephonic transmission while freely transmitting a band of frequencies within said limit, and a second broad band filter associated with said second repeater and so arranged as to substantially suppress frequencies below said limit while freely transmitting a band of frequencies above said limit.
8. In a transmission system a plurality of repeaters operated in parallel and adapted to amplify different ranges of frequencies, means in the input circuit of each repeater to determine the range of frequencies transmitted to the repeater, a balancing circuit for each repeater, and means in each balancing circuit having electrical characteristics simulating the electrical characteristics of said first mentioned means.
9. In a transmission system a plurality of repeaters operated in parallel and adapted to amplify different ranges of frequencies, means in the input circuit of each repeater to determine the range of frequencies to be amplified by each repeater, a balancing circuit for each repeater, and means in each

balancing circuit having electrical characteristics simulating the electrical characteristics of said first mentioned means.

10. In a transmission system a plurality of repeaters operated in parallel and adapted to amplify different ranges of frequencies, a broad band filter in the input circuit of each repeater, a balancing circuit for each repeater, and means in each balancing circuit having electrical characteristics simulating the electrical characteristics of the corresponding filter.

11. In a transmission system a plurality of repeaters operated in parallel and adapted to amplify different ranges of frequencies, a broad band filter in the input circuit of each repeater, a balancing circuit for each repeater, and a broad band filter in each balancing circuit for balancing the corresponding filter in the input circuit. 15

In testimony whereof, I have signed my name to this specification this 18th day of June 1919.

LLOYD ESPENSCHIED.
